DIFFERENTIAL IONIC ANALYZER

Robert V. Seaman, Denver, Colo.

Application May 8, 1945, Serial No. 592,711

16 Claims. (Cl. 73—18)

1

This invention relates to mass spectrometry for determining the mass, abundance and character of the isotopes of elements and more particularly to a mass spectrometer or differential ionic analyzer which will divide the negative ions and fragments from the positive ions and fragments so that the mass and abundance of each may be determined simultaneously and independently as differentiated from the usual spectrometer in which only the ions of one polarity are impinged against a single target or collector charged with the opposite polarity.

Another object of the invention is to provide an analyzer in which both quantitative electronic reactions of the ions and the spectroscopic analysis thereof can be made simultaneously and independently.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

The drawing diagrammatically illustrates the elements of the improved differential ionic analyzer. Briefly, the improved spectrometer or differential analyzer ionizes any desired element or combination of elements in either the gaseous, liquid, or solid stages; divides the positive ions from the negative ions; and thence impinges the ions of one polarity upon one analyzing target and the ions of the opposite polarity upon a second independent target. The targets are each equipped with apparatus for making a complete ionic and spectrographic analysis of the ions of the respective polarities.

The above is accomplished by means of a Y-tube, in the stem of which the element or elements to be analyzed are received and ionized. The two legs of the Y-tube terminate in target bulbs and are provided with means for attracting ions of opposite polarities respectively.

The Y-tube is constructed of any suitable material such as "pyrex" glass. The stem of the tube is divided into a feed chamber 10 and an ionization chamber 11. The feed chamber 10 is separated from the ionization chamber 11 by means of a valve 12. A gas or vapor feed tube 13 opens into the feed chamber 10 and is controlled by means of a suitable stopcock 14. The extremity of the feed chamber 10 is closed by means of a

2

feed cock 15 and the extremity of the ionization chamber 11 terminates in a control valve 16.

Beyond the control valve 16, the tube is divided to form two flaring leg tubes which will be herein designated as the negative leg tube 17 and the positive leg tube 18. The tubes 17 and 18 terminate in target bulbs 19 and 20, respectively. An evacuating nipple 35, controlled by means of a vacuum cock 36, communicates with the interior 10 of the tubes 17 and 18.

An ion receiving plate or target 21 is positioned within each of the bulbs 19 and 20 in axial alignment with the tubes 17 and 18, respectively. The angle of the targets is such as to reflect light 15 traveling along the axes of the tubes 17 and 18 through focusing lenses 22 and through spectrographic slits 23 to reflecting prisms 24. The light rays from the prisms 24 are fed to any desired photographic or spectrographic apparatus for 20 determining the elemental nature of the ions.

An electrically heated vaporizing screen 25 is placed in the ionization chamber 11. The screen may have any desired construction, such as a continuous folded length of resistance wire supplied with current through suitable conductors 26. The ionization chamber is also provided with one or more sets of electronic plates 27 and filaments 28 upon which controlled voltages may be impressed through suitable conductors 29. That 25 portion of the ionization chamber containing the plates and filaments is surrounded by means of a magnetizing solenoid which will be herein designated the stem solenoid 30. The two tubes 17 and 18 are each surrounded by means of a pair of 30 spaced magnetizing solenoids which will be herein designated the leg solenoids 31 and 32.

Metallic beam concentrating sleeves 33 and 34 are axially positioned within the tubes 17 and 18 and within the solenoids 31 and 32, respectively. 40 The sleeves 34 are of smaller diameter than the sleeves 33 for reasons to be later described.

The interior of each of the bulbs 19 and 20 is coated with an electrical conducting coating 37 connected with a ground lead 39. The ion collector or target 21 in the bulb 19 is connected through a negative conductor 38 with the negative terminal of any suitable direct current source having a controllable, variable potential up to say 15,000 volts. The target 21 in the bulb 20 is similarly connected through a positive conductor 43 with the positive terminal of the same or a similar source.

The apparatus is designed to handle either gases, liquids or solids. Gases are introduced 55 through the gas inlet 13 and the stopcock 14.

Solids and liquids are introduced through the feed cock 15 onto a tilting shelf 41 in the feed chamber. The shelf 41 can be released from the exterior in any desired manner such as through the medium of an electromagnet 42 acting on a retractable latch 40.

Let us assume that a sample of material is to be ionically analyzed. The sample is placed on the shelf 41 and the valve 15 and stopcock 14 are closed. The valves 12 and 16 are opened and the entire interior of the Y-tube is evacuated through the vacuum nipple 35 to a pressure of, say 10^{-4} mm. Hg. After the evacuation has been completed, the cock 36 and the valve 16 are closed. The magnet 42 is then energized to allow the shelf 41 to tilt allowing the sample of material to fall onto the hot screen 25. The hot screen immediately vaporizes and partially ionizes the sample. This vapor is further ionized by bombardment of the stream of electrons being emitted by the first filament 28 accelerated by a potential of from 70 to 100 volts and thence by a second and more intense bombardment from the electrons of the second filament 28 accelerated by a still higher potential on the order of 1000 to 3000 volts. Direct current is being simultaneously supplied to the solenoid 30 so that the liberated ions are immersed in a strong magnetic field, which affects an ionic rotation and centrifugal separation thereof in consequence of their differences of electronic mass.

The valve 16 is now opened and the beam of spiraling ions is drawn to the entrances of the two leg tubes 17 and 18. The negatively charged target 21 in the bulb 19 exerts a strong attraction for the positive ions in the beam and similarly repels the negative ions. The positively charged target 21 in the bulb 20 acts reversely and attracts the negative ions so that the ions in the beam are separated and divided at this point according to their individual polarities.

The concentrating sleeves 33 and 34 in the leg tubes are charged with the same polarity as the ions flowing therethrough, that is, the sleeves in the tube 17 are positively charged and the sleeves in the tube 18 are negatively charged. They therefore act to repel the passing ions into compact axial cores or beams before they strike their respective targets. This regimentation and control of the flow of the ions is assisted by the centrifugal effect produced by the magnetic fields of the solenoids 31 and 32. By control of the relative potentials on the targets and the concentrating sleeves and the currents feeding the solenoids, absolute control of the ion beams is attained.

The ions in the beams strike their respective targets where they are still further ionized and impress a potential on the target in accordance with their masses and abundance as in the usual electrometer. In this case, however, due to the preliminary division of the ions each target receives only the ions of one polarity.

Each of the ion collectors or targets 21 is connected through the medium of a conductor 38 or 43 with any suitable electronic detector tube to amplify any current impulses received due to the impingement of the ions on the targets 21 and feed them to suitable amplifying circuits. The current from the amplifying circuits is measured by any sensitive electronic method or is fed to a galvanometer (not shown) which deflects through an angle proportional to the abundance of the ions in each beam. The resulting deflections may be recorded in any desired manner, such as photo-

tographically, to produce an ionic abundance record of the given sample. The lighter ions will, of course, attain greater velocity than the heavier ones and will strike the targets first followed by the successively heavier ions. Since the voltage developed is a characteristic of the velocity the resulting curve developed will give a differentiation between individual classes of ions.

By control of the vacuum and the impressed potential the stream of ions can be made to glow with ionic light. The beams therefore assume the nature of light beams and the light therefrom is reflected by the targets through the lenses 22 and the slits 23 to any suitable spectrograph 15 where the spectrum of the ions may be studied and/or recorded. Thus, a spectrographic qualitative analysis of the divided beams can be made simultaneously with the electronic quantitative analysis.

If desired, the targets may be activated with a fluorescent coating, in which case fluorescent light will be admitted by the impact of the ions and this light will be focused through the lenses 22 and the slits 23 for analysis, consideration, of course, being given to the effect of the fluorescent coating on the resulting spectrum.

Another way in which the light may be produced is by the ionization of impact of the ions on the target which may also be used for spectrographic analysis.

Stray ions outside of the beam strike the conducting coating 37 in the bulbs and their charges are dissipated through the ground leads 39.

In the above described method of operation, a single evacuation of the tubes is described. It may be desirable in some cases to allow the vacuum pump to operate continuously so as to evacuate excess vapors and gases which may be formed.

The Y-tube may be cleaned out after an experiment or operation in any desired manner. One method is to fully vaporize any substances which have been introduced and withdraw them through the evacuating nipple as a vapor. After use on gases, the tubes may be flushed with nitrogen and the latter evacuated by suction.

While a specific form of the improved analyzer has been diagramed and described herein together with suggested circuits for obtaining the necessary electrical results, it is to be understood that these are only suggestive and that the methods and means for producing the desired currents and potentials form no part of the present invention.

Having thus described the invention, what is claimed and desired secured by Letters Patent is:

1. A differential ionic analyzer comprising: an ionization chamber; a negative tube extending from said chamber; a positive tube extending from said chamber; a negatively charged ion target at the extremity of the negative tube for attracting positive ions; and a positively charged ion target at the extremity of the positive tube for attracting negative ions.

2. A differential ionic analyzer comprising: an ionization chamber; a negative tube extending from said chamber; a positive tube extending from said chamber; a negatively charged ion target at the extremity of the negative tube for attracting positive ions; a positively charged ion target at the extremity of the positive tube for attracting negative ions; and indicating means in conjunction with each target to independently indicate the characteristics of the ions impinged upon each target.

3. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; a negative tube extending from said ionization chamber; a positive tube extending from said ionization chamber, each of said tubes terminating in a target bulb; a negative ion target in the bulb at the extremity of the negative tube; a positive ion target in the bulb at the extremity of the positive tube; and electronic means for indicating the ionic impingement on each of said targets.

4. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; an electron emitting element in said ionization chamber for bombarding the vapor therein; a negative tube extending from said ionization chamber; a positive tube extending from said ionization chamber, each of said tubes terminating in a target bulb; a negative ion target in the bulb at the extremity of the negative tube; a positive ion target in the bulb at the extremity of the positive tube; and electronic means for indicating the ionic impingement on each of said targets.

5. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; a negative tube extending from said ionization chamber; a positive tube extending from said ionization chamber, each of said tubes terminating in a target bulb; a negative ion target in the bulb at the extremity of the negative tube; a positive ion target in the bulb at the extremity of the positive tube; electronic means for indicating the ionic impingement on each of said targets; and a solenoid surrounding said ionization chamber for imparting rotation to the ions therein.

6. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; a negative tube extending from said ionization chamber; a positive tube extending from said ionization chamber; each of said tubes terminating in a target bulb; a negative ion target in the bulb at the extremity of the negative tube; a positive ion target in the bulb at the extremity of the positive tube; electronic means for indicating the ionic impingement on each of said targets; and a metallic focusing sleeve in each of said tubes, said sleeves being charged with a polarity corresponding to that of the ions flowing in that tube.

7. A differential ionic analyzer comprising: an ionization chamber; a negative tube extending from said chamber; a positive tube extending from said chamber; a negatively charged ion target at the extremity of the negative tube for attracting positive ions; a positively charged ion target at the extremity of the positive tube for

attracting negative ions; and means for receiving light reflected from said targets.

8. A differential ionic analyzer comprising: an ionization chamber; a negative tube extending from said chamber; a positive tube extending from said chamber; a negatively charged ion target at the extremity of the negative tube for attracting positive ions; a positively charged ion target at the extremity of the positive tube for attracting negative ions; means for receiving light reflected from said targets; and a spectrographic analyzing means for each target operable in consequence of the receipt of said reflected light.

9. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; a negative tube extending from said ionization chamber; a positive tube extending from said ionization chamber, each of said tubes terminating in a target bulb; a negative ion target in the bulb at the extremity of the negative tube; a positive ion target in the bulb at the extremity of the positive tube; electronic means for indicating the ionic impingement on each of said targets; a sample receiving shelf in said feed chamber; and means for causing said shelf to deposit the received sample on said heating element.

10. A differential ionic analyzer comprising: a feed chamber; means for sealing said feed chamber from the atmosphere; an ionization chamber; valve means for placing said two chambers in communication; a heating element in said ionization chamber for vaporizing a sample to be analyzed; a negative tube extending from said ionization chamber; a positive tube extending from said ionization chamber, each of said tubes terminating in a target bulb; a negative ion target in the bulb at the extremity of the negative tube; a positive ion target in the bulb at the extremity of the positive tube; electronic means for indicating the ionic impingement on each of said targets; means for introducing a gas into said feed chamber; and means for evacuating gases from all of said chambers and tubes.

11. A differential ionic analyzer comprising: a stem tube; means for introducing a sample to be analyzed into said stem tube; an ionization chamber formed in said stem tube; a negative leg tube extending from said stem tube; a positive leg tube extending from said stem tube; a target bulb formed on the extremity of each leg tube; means for evacuating all of said tubes; an ion target positioned within each of said bulbs in axial alignment with its respective leg tubes; a focusing lens positioned in optical alignment with each of said targets; means for impressing a positive electrical charge on the target in the positive tube; and means for impressing a negative electrical charge on the target in said negative tube.

12. A differential ionic analyzer comprising: a stem tube; means for introducing a sample to be analyzed into said stem tube; an ionization chamber formed in said stem tube; a negative leg tube extending from said stem tube; a positive leg tube extending from said stem tube; a target bulb formed on the extremity of each leg tube; means for evacuating all of said tubes; an ion target positioned within each of said bulbs in axial alignment with its respective leg tube; a focusing lens positioned in optical alignment with each of said targets; means for impressing

a positive electrical charge on the target in the positive leg tube; means for impressing a negative electrical charge on the target in said negative leg tube; and an independent spectrographic apparatus receiving the light from each of said lenses for determining the elemental nature of the ions in each bulb.

13. A differential ionic analyzer comprising: a stem tube; means for introducing a sample to be analyzed into said stem tube; an ionization chamber formed in said stem tube; a negative leg tube extending from said stem tube; a positive leg tube extending from said stem tube; a target bulb formed on the extremity of each leg tube; means for evacuating all of said tubes; an ion target positioned within each of said bulbs in axial alignment with its respective leg tube; means for impressing a positive electrical charge on the target in the positive leg tube; means for impressing a negative electrical charge on the target in said negative leg tube; an electrically heated vaporizing grid in said stem tube; ionizing means in said stem tube; and indicating means operable in consequence of the impingement of ions on said targets.

14. A differential ionic analyzer comprising: a stem tube; means for introducing a sample to be analyzed into said stem tube; an ionization chamber formed in said stem tube; a negative leg tube extending from said stem tube; a positive leg tube extending from said stem tube; a target bulb formed on the extremity of each leg tube; means for evacuating all of said tubes; an ion target positioned within each of said bulbs in axial alignment with its respective leg tube; means for impressing a positive electrical charge on the target in the positive leg tube; means for impressing a negative electrical charge on the target in said negative leg tube; an electrically heated vaporizing grid in said stem tube; ionizing means in said stem tube; indicating means operable in consequence of the impingement of ions on said targets; an electrically energized solenoid surrounding said stem tube; and similar solenoids surrounding the two leg tubes for imparting ionic rotation to the ions therein.

15. A differential ionic analyzer comprising: a stem tube; means for introducing a sample to be analyzed into said stem tube; an ionization chamber formed in said stem tube; a negative

5

leg tube extending from said stem tube; a positive leg tube extending from said stem tube; a target bulb formed on the extremity of each leg tube; means for evacuating all of said tubes; an ion target positioned within each of said bulbs in axial alignment with its respective leg tube; means for impressing a positive electrical charge on the target in the positive leg tube; means for impressing a negative electrical charge on the target in said negative leg tube; an electrically heated vaporizing grid in said stem tube; ionizing means in said stem tube; indicating means operable in consequence of the impingement of ions on said targets; tubular, metallic, beam concentrating sleeves axially positioned within each of said leg tubes, said sleeves being charged with an electrical polarity corresponding to that of the charge of the ions flowing through the respective tubes.

16. A differential ionic analyzer comprising: a stem tube; means for introducing a sample to be analyzed into said stem tube; an ionization chamber formed in said stem tube; a negative leg tube extending from said stem tube; a positive leg tube extending from said stem tube; a target bulb formed on the extremity of each leg tube; means for evacuating all of said tubes; an ion target positioned within each of said bulbs in axial alignment with its respective leg tube; means for impressing a positive electrical charge on the target in the positive leg tube; means for impressing a negative electrical charge on the target in said negative leg tube; an electrically heated vaporizing grid in said stem tube; ionizing means in said stem tube; indicating means operable in consequence of the impingement of ions on said targets; an electrical conducting lining within each of said bulbs for collecting stray ions; and means for carrying off the charge from said lining.
